(57) **CLAIM**

The ornamental design for a bag used for sample or collection, as shown and described.

DESCRIPTION

FIG. 1 is a front, top, right perspective view of a bag used for sample or collection, showing the new design;

FIG. 2 is a rear, bottom, left perspective thereof;

FIG. 3 is a front elevation view thereof;

FIG. 4 is a rear elevation view thereof;

FIG. 5 is a left side view thereof;

FIG. 6 is a right side view thereof;

FIG. 7 is a bottom plan view thereof; and,

FIG. 8 is a top plan view thereof.

The broken lines of uneven length illustrate the boundary of the claimed design and form no part thereof. The broken lines of even length depict portions of the bag used for sample or collection that form no part of the claimed design. The contrast in appearance of materials is shown by stipple and line shading in some areas.
